UNITED STATES PATENT OFFICE.

WILLIAM L. BYRNE AND HARVEY A. BEESLEY, OF LOS ANGELES, CALIFORNIA.

KNOCKDOWN CABINET.

Application filed June 1, 1925. Serial No. 34,094.

To all whom it may concern:

Be it known that we, WILLIAM L. BYRNE and HARVEY A. BEESLEY, citizens of the United States, and residents of the city of Los Angeles, in the county of Los Angeles and State of California, have invented a new and useful Knockdown Cabinet, of which the following is a specification.

This invention relates to cabinets, such as may be used for radio sets, and especially to cabinets that may be readily set up from its component parts without the aid of any tools or fastening means.

It is one of the objects of our invention to make it possible to provide an inexpensive and sturdy cabinet, that is not only ornamental, but that can be readily assembled or taken apart, as for shipment or the like.

Another object of our invention is to provide a shelf structure in a knockdown cabinet in which the shelves serve also as the braces for the cabinet to render it rigid.

Still another object of our invention is to provide a radio cabinet that can readily be made to accommodate radio panels of different sizes.

Our invention possesses many other advantages, and has other objects which may be made more easily apparent from a consideration of a form of our invention. For this purpose we have shown an embodiment in the drawings accompanying and forming part of the present specification. We shall now proceed to describe this embodiment in detail, which illustrates the general principles of our invention; but it is to be understood that this detailed description is not to be taken in a limiting sense, since the scope of the invention is best defined by the appended claims.

Referring to the drawings:

Figure 1 is a front elevation of an assembled radio cabinet embodying our invention;

Figure 2 is an isometric view, showing the cabinet partly assembled, and a few other parts in position to be assembled;

Figure 3 is a horizontal sectional view taken along plane 3-3 of Fig. 1;

Fig. 4 is a plan view of one of the shelves used; and

Fig. 5 is an elevation of a part of one of the sides.

The cabinet in this instance is shown as made from wood, although other material can if considered desirable, be used. The

cabinet has two side members 11 (Figs. 2 and 5) which can be made from a solid piece or from a number of pieces permanently attached. Each side member preferably includes a pair of corner posts 12, shown as of substantially square cross section. The bottom portions of these posts can be formed into ornamental legs 13, which serve to support the entire cabinet at a suitable height. Between the corner posts for each side member 11, there is a paneling 14 or the like, which extends entirely across from one post to the other. In the present instance these panels are shown as glued or otherwise fastened in grooves located in the contiguous faces of the posts 12, and as being provided at the top and bottom with border strips 15 and 16. These side members 11 could obviously be made in other equivalent ways.

One of the important features of our invention resides in the manner in which the two sides 11 are held rigidly in spaced relation to each other by the aid of separable elements. For this purpose, we use one or more shelf structures 17 and 18, which of course also serve for the accommodation of the apparatus to be supported in the cabinet. Each shelf is provided at each of its ends with a cleat 19, fastened to the shelf, and having tongues 20 (Figs. 2, 3 and 4) which extend transversely of the cleat. These tongues are arranged to enter snugly into grooves 21 provided in the inner faces of the posts 12. The cleats and the tongues are moreover so proportioned that the ends of the shelves lie closely to the inner surface of the sides 11, as indicated in Fig. 3. Since the cleats 19 and the shelves form a considerable area of contact at these places, and since the tongue and groove connection holds the parts tightly against each other, it is seen that a rigid structure is secured. This is enhanced when, as in the present instance, more than one shelf is utilized as braces.

In order to ensure that the shelves 17 and 18 will be properly spaced apart a predetermined distance, there are preferably provided on the inner surface of members 11, a pair of shelf rests 22, upon which the ends of the shelves are accommodated.

It is further to be noted, as shown most clearly in Fig. 2, that grooves 21 do not extend entirely to the top of posts 12, but stop short thereof. It is thus necessary, when assembling shelves 17 and 18 with

sides 11, to incline these shelves so as to permit placing the ends of the shelves in slantwise between the posts 12, and then to return them to a horizontal position, while 5 tongues 20 simultaneously enter the grooves 21.

The back for the cabinet can be provided in any well known manner, but we prefer to arrange it so that it can be separated into 10 several parts for convenience in transporting. Accordingly we show the back in Fig. 2 as made up of a plurality of thin sheets or boards, 23 and 24. These are accommodated at their lateral edges in grooves 25 15 formed in the posts 12; the grooves being sufficiently tight to form a good joint. In order to conceal the place where the two parts 23 and 24 come together, there is provided a strip 26 grooved at the top and 20 bottom, arranged to take the bottom edge of the board 24 in the upper groove, as well as the top edge of board 23 in the lower groove. The strip 26 also provides a panelled effect for the back of the cabinet.

25 A top strip 27 having a bottom groove for the top edge of board 24 is also provided in order to form a wide frame at the top of the cabinet. This strip has tongues 28 fitting snugly within grooves 25. All of the 30 parts 23, 26, 24, and 27 can be readily slipped in and out of place, while the shelves 17 and 18 are in position.

The front of the cabinet is also preferably sectional. For example, a lower section 39 is provided, which is panelled as shown, having a top strip 30 and a lower strip 31. This section 39 is preferably permanently fastened to these top and lower strips, and its edges enter into grooves 42 40 similar to grooves 25. Furthermore, at about the central portion of this lower section 39, there is a veneered panel 32, which has a cut-out ornamental design on it. It is intended that a loud speaker be accommodated immediately behind this design in the cabinet; but of course other forms for the lower section could also be used.

The upper border strip 30 has a groove 50 36 in its upper edge, to accommodate the elements that form the upper section. This upper section is preferably formed in such manner that a radio panel 33 can be conveniently and separably supported in the 55 grooves 36 at the bottom edge of the panel. The sides of the panel 33 can be accommodated in grooves in the border strips 34, which have tongues 35 at their bottoms entering into the groove 36. A pair of panels 37, one at each side of the panel 33, have their bottom edges accommodated in groove 60 36; one side edge of each is accommodated, as shown, in Fig. 3, in vertical grooves in the contiguous border strip 34, while the other side edge is accommodated in that groove

42 which is adjacent. It is evident that various arrangements can be provided for three panels 33 and 37, as regards size and relative position.

The top edges of all three panels are held 70 in a groove 38 formed in the bottom of a border strip 39, similar in all respects to the border strip 27 at the back of the cabinet. This strip also has tongues (such as 28 on strip 27) which enter snugly into 75 grooves 42. Furthermore the vertical border strips 34 have tongues 40 at their tops that enter into the groove 38.

A cover 41 rests on top of the cabinet. This may be either hinged at the back, or 80 else cleats can be fastened to the lower side of the cover, which fit into the corners of the top and serve to align the cover with respect thereto.

The radio apparatus may be distributed 85 in any convenient or desired manner in the cabinet and on the shelves 17 and 18. The cabinet can very readily be modified to take care of various sizes of radio panels, as by proper choice of the size of the panels 90 37. The connections for the apparatus can be passed from one shelf to the other at the front or rear of the shelves, there being sufficient clearance for this, as indicated most clearly in Fig. 2.

The description of the cabinet is now complete. There remains to be described merely the manner in which the cabinet may be assembled and taken apart. First of all, the shelves 17 and 18 are positioned properly as regards sides 11, to form the structure illustrated in Fig. 2. Then parts 23, 26, 24 and 27 can in this order be placed one on top of another between grooves 25. The back is then complete. For the front, the lower section 39 is first placed in position between grooves 42; then panels 37 are 100 spaced in grooves 42 and 36. The border strips 34 can be then positioned, and afterward, the panel 33. Then it is merely necessary to place strip 39 over the panels, and the assembly is complete except for the placing of cover 41.

It is evident that the assembly takes less time than it does to describe it; and that a 105 rigid, although inexpensive construction, is provided thereby. The manner of taking the cabinet apart is evident from the foregoing.

It is of course possible to utilize the cabinet for other than radio apparatus, although it is best fitted for such use.

When the cabinet is taken apart, it can readily be packed in a small space. The 110 largest parts are the side members 11. The fact that the front and back are both made from several pieces makes it possible to secure this compactness. Due to this feature, the shipping or transportation cost is very 115 materially reduced. Another important

feature is that all of the parts can be very inexpensively manufactured, so that the ultimate cost to the purchaser is maintained at a low value.

5 A divisional application Serial No. 77,509, filed December 24, 1925, is directed to subject-matter not covered in the claims of the present application.

We claim:

- 10 1. In a radio cabinet, a strip having a groove in its upper surface, side portions having vertically, oppositely formed grooves, a top strip arranged with a groove in its lower surface, said grooves defining 15 an aperture having a groove around its inner edge, a pair of detachable panel elements, each resting at its bottom edge in the lower groove at one side edge in a side groove, and at its top edge in the upper groove, and a pair of detachable laterally shiftable upright grooved strips in which the other edges of the panels are respectively placed, said strips also having tongues resting in the top and bottom grooves, as well 20 25 as grooves defining with said top and bottom grooves, an aperture in which a radio panel can be detachably supported at its edges by the aid of said grooves.
2. In a knock-down radio cabinet, means forming separable side and back members, said side members having inwardly facing grooves in the edges thereof, a bottom portion forming part of the front of the cabi-

net and having a groove in its upper edge, a detachable top portion engaging the 35 grooves in the side members and having a downwardly opening groove opposite the groove in the bottom portion, a pair of vertically disposed laterally shiftable strips, each detachably engaging at its ends, in the 40 grooves in the bottom and top portions, said strips being separated to provide a space for a radio panel.

3. A knock-down radio cabinet having separable side, back, and front members, 45 said side members having inwardly facing grooves in the edges thereof, said front member comprising lower and upper sections, the said lower section having a groove in its upper edge and a sound exit opening 50 intermediate its ends, said upper section comprising two vertically and one horizontally disposed separable strips provided with tongues on the ends thereof, 55 said horizontal strip being provided with a downwardly opening groove, said vertical strips being disposed between said lower section and said horizontal strip with their tongue slidably engaging said grooves, and detachable panel elements filling the 60 spaces between said vertical strips and said side members, the said vertical strips being separated to provide a space for a radio panel.
